UNITED STATES PATENT OFFICE.

JAMES CONROYD, OF CHICAGO, ILLINOIS.

RADIATOR VALVE.

Application filed December 22, 1921. Serial No. 524,334.

To all whom it may concern:

Be it known that I, JAMES CONROYD, a citizen of the United States, residing at Chicago, in the county of Cook and State 5 of Illinois, have invented a certain new and useful Improvement in Radiator Valves, of which the following is a specification.

This invention relates to a radiator valve construction and particularly to a float and 10 float assembly for such valves. It has for one object to provide means which will prevent the float from being drawn down upon its seat by the suction within the system when the level of water within the float 15 chamber has actually risen to a point where it should raise the float. Another object is to provide a radiator float and float assembly in which the action of the float is entirely unaffected by suction within the system. 20 Other objects will appear from time to time throughout the specification and claims.

My invention is illustrated more or less diagrammatically in the accompanying drawings, wherein:

25 Figure 1 is a vertical cross section of the valve and float chamber with the float in elevation;

Fig. 2 is a section taken on line 2—2 of Fig. 1;

30 Fig. 3 is a view in elevation with parts in section and parts broken away showing a modified form.

Like parts are designated by like characters throughout.

35 A is a valve housing having a central float chamber A¹, an inlet passage A² and a discharge passage A³. Mounted within the discharge passage is the valve seat A⁴. The top of the valve housing is open and is 40 adapted to be closed by the screw threaded cap A⁵ which is hollow as at A⁶ as shown. The cap is provided with a perforation A⁷ which communicates with the float chamber and a plurality of perforations A⁸.

45 Adjacent the perforations A⁸ when the cap is screwed in place as shown in the figures is a segmental cavity A⁹. Communicating at one end with this cavity A⁹ and at the other with the discharge passage A³ is a 50 passage A¹⁰. The lower section of the cap A⁵ is perforated as at A¹¹ and provided with the upwardly extending boss A¹² about such perforation.

B is a connection of any suitable type by 55 means of which water from the radiator is introduced into the float chamber. Within

the float chamber is mounted a float C. Positioned centrally within this float is a hollow tube C¹ which lies normally within the perforation A¹¹ of the cap A⁵. At its lower end the tube is narrowed and provided with the beveled portion C² which is adapted to be seated in the valve seat A⁴ to close the valve to prevent discharge of water through the valve and over the seat A⁴ but 60 to permit passage of steam through the tube C¹ into the passage A³, thus balancing the suction and pressure.

In the form shown in Figure 3 the upwardly extending boss A¹² is omitted and in 70 its place a downwardly extending boss A¹³ about the perforation A¹¹ is substituted. In this form also the tube C¹ is enlarged and surrounds the boss A¹³.

The use and operation of my invention 75 are as follows:

When the water level is not sufficient to raise the float, the float remains seated as shown particularly in Figure 1. When the water level rises sufficiently to raise the float, 80 the float is unseated and discharge of water takes place until the level is sufficiently reduced to allow the float again to become seated and prevent further discharge.

With such systems there is always a considerable degree of suction in the discharge pipe and such suction tends to hold the float down in opposition to its natural buoyancy and to hold it seated after the water level has become such as normally to 90 raise the valve, and thus discharge of water at the proper time is prevented and the operation of the valve is unsatisfactory. This tendency in valves of this type is so well recognized that practically every such valve 95 now on the market is provided with a bypass by the manipulation of which the float chamber may be cut out, and the water may be caused to flow directly from the radiator to the discharge port and thus discharge of 100 water from the radiator is entirely independent from the float or operation of the valve.

In my invention I provide means whereby the suction in the discharge line may be balanced. Thus through the air passage 105 at the side which communicates with the hollow cap at the top of the valve and through the hollow tube in the end of the valve air may be drawn either directly through the valve or through the passage at 110 the side of the valve, each of which is in communication with the interior of the float

chamber. By means of this arrangement it is impossible to set up such unbalanced suction as will hold the valve on its seat in opposition to its normal buoyancy, and thus the operation of the valve is effected only by the variation of the water level and is entirely independent of the suction in the discharge line or elsewhere in the system.

I claim:

10. 1. The combination of a radiator valve having a float chamber, water inlet and outlet ports communicating with such chamber, a float valve in such chamber, with a pair of independent air conduits communicating with such float chamber and with the discharge from the valve, one of such conduits lying within but normally separated throughout its length from such float chamber, and the other conduit lying wholly outside the float chamber.
20. 2. The combination of a radiator valve having a float chamber, water inlet and outlet ports communicating with such chamber, a float valve in such chamber, with a pair of independent air conduits communicating with such float chamber and with the discharge from the valve, one of such conduits lying within but normally separated throughout its length from such float chamber, and the other conduit lying wholly outside the float chamber, said first mentioned conduit passing through said float.
30. 3. In a radiator valve a float chamber, water inlet and outlet openings communicating with such chamber, a water discharge connection below such water outlet opening, a hollow cap adapted to close such float chamber, and a free communication from the interior of such valve chamber to the interior of such cap, and a pair of air com-

munication conduits from the interior of said cap to such discharge connection beneath said outlet opening.

4. In a radiator valve a valve casing provided with a float chamber, an opening in the bottom of said casing communicating with said float chamber, a water free air passage communicating with said opening at all times and communicating with the float chamber at its top, said float chamber provided with a connection for a radiator, whereby the contents of the radiator may flow into the float chamber, and a valve stem within said float chamber adapted to close the bottom opening, to prevent discharge from the float chamber, said valve stem being hollow and provided with a connection independent of the float chamber and through it whereby air may circulate, and the float adapted to control said valve in response to variation in the level of liquid in the casing.

5. In a radiator valve, a valve casing provided with a float chamber, an inlet opening and a discharge opening for said float chamber, a float in said float chamber provided with a valve part adapted to be seated in the discharge opening and to control discharge therethrough, and means for balancing suction on said valve and float comprising a liquid free air passage through said valve and float, and an additional liquid free air passage communicating with the top of said valve casing and with the outlet connection of said valve at a point independent of said valve seat.

Signed at Chicago, county of Cook and State of Illinois, this 20th day of December, 1921.

JAMES CONROYD.
